Des. 228,718

Patented Oct. 23, 1973

228,718

MULTIPLE SEATING FURNITURE SUPPORT

Gideon A. Kramer, Seattle, Wash., assignor to American
Desk Manufacturing Company, Temple, Tex.

Filed July 1, 1971, Ser. No. 159,090

Term of patent 14 years

Int. Cl. D6—06

U.S. Cl. D6—196

Fig. 1.

Fig. 2.

FIG. 1 is a side elevation view of the multiple seating furniture support showing my design; and

FIG. 2 is a rear elevation view of the multiple seating furniture support.

I claim:

The ornamental design for a multiple seating furniture support, as shown.
